UNITED STATES PATENT OFFICE

ALPHIE ROULEAU AND PAUL NADEAU, OF BARRE TOWN, VERMONT

VEHICLE SPRING

Application filed September 15, 1931. Serial No. 562,958.

This invention relates to certain new and useful improvements in vehicle springs, and has as its primary object the provision of a laminated or leaf spring capable of providing a quicker action thus providing more easy riding than heretofore has been obtained by leaf springs now in use.

A still further object of the invention is to provide a vehicle spring comprising a plurality of superimposed leaves, together with shackles or U-shaped clamps embracing the spring adjacent the end thereof and respectively provided with a pair of rollers receiving the lowermost springs therebetween.

Other objects and advantages of the invention will become apparent from a study of the following description, taken in connection with the accompanying drawing wherein:

Figure 1 is an elevational view of the spring, and

Figure 2 is a vertical transverse sectional view taken substantially on line 2—2 of Figure 1.

With reference more in detail to the drawing, it will be seen that the leaf spring in the single embodiment illustrated comprises a plurality of leaves varying in length and respectively bowed slightly longitudinally.

The leaves are arranged in superimposed relation and adjacent each end of the spring is an inverted U-shaped clamp or shackle 5, and inwardly from the clamp 5 similar slightly longer clamp 6.

Each of the clamps 5 and 6 adjacent its open lower end has journalled between opposed portions thereof as at 7 a roller 8 contacting the under face of the lowermost longer leaf 9.

Also, each of the clamps 5 and 6 above the roller 8 has journalled between opposed portions thereof as at 10 a roller 11 disposed between and contacting with a leaf 12 disposed upon the leaf 9, and a relatively shorter leaf 13 separated from the leaf 12 by a pair of varied length leaves 14 and 15.

As shown, the longer leaf 15 rests upon the leaf 12, and a shorter leaf 14 is interposed between leaf 15 and the leaf 13.

The clamps 5 at their closed ends are

riveted as at 16 to the ends of the leaf 13, in spaced relation to the ends of a leaf 17 which at its end terminates short of the leaf 13.

The leaf 17 extends, at its ends through and beyond the clamp 6, while a relatively shorter leaf 18 terminates at its ends between opposed sides of the clamp 6, and at said end riveted to the upper closed end of the clamp 6 as at 19.

The uppermost leaf 20 rests on the leaf 18 and is slightly shorter than the leaf 15.

All these leaves are connected together in superimposed relation through the medium of a bolt 21 passing through the leaves intermediate the ends thereof and having a nut 65 or the like 22 threadedly engaged with the free end thereof.

As is apparent, the leaves 14 and 15 provide for suitably spacing the leaves 12 and 13, to accommodate therebetween rollers 11 of the clamp, the larger clamp 6 being placed inwardly toward the transverse center of the spring to serve to strengthen the body thereof.

In providing a spring with the arrangement of beams, clamps and rollers just described, the spring is susceptible to quicker action, making for easy rising, and, by reason of the general construction of the spring arrangement of clamp and rollers, there is less chance of snapping and breaking of the leaf.

Even though we have herein shown and described the preferred embodiment of the invention, it is to be understood that the same is susceptible of further changes, modifications and improvements coming within the scope of the appended claims.

Having thus described our invention, what we claim as new is:

1. A vehicle leaf spring comprising a plurality of relatively elongated lower leaves, and a plurality of relatively shorter upper leaves separated from the first named leaves by a plurality of intermediate leaves of varying length, clamps embracing the first and second named leaves at opposite ends of the spring, and rollers carried by said clamps and arranged in the space provided between the first and second named springs, and engaging the opposed surfaces of the springs.

2. A vehicle spring comprising a plurality

- of superimposed leaves, a bolt extending through the leaves intermediate the ends thereof, said leaves including a plurality of relatively elongated lower leaves, a plurality of upper leaves progressively decreasing in length, and a plurality of intermediate leaves varying in length and arranged between the upper and lower leaves, clamps embracing the longer one of the uppermost leaves and said lower leaves at relatively opposite ends of the spring, additional clamps inwardly from the first named clamps embracing the upper and lower springs and a pair of rollers carried by each of the clamps and receiving there-between the lowermost spring; said rollers normally contacting the surfaces of the springs.
3. A vehicle spring comprising a plurality of superimposed leaves, a bolt extending through the leaves intermediate the ends thereof, said leaves including a plurality of relatively elongated lower leaves, a plurality of upper leaves progressively decreasing in length, and a plurality of intermediate leaves varying in length and arranged between the upper and lower leaves, clamps embracing the longer one of the uppermost leaves and said lower leaves at relatively opposite ends of the spring; additional clamps inwardly from the first named clamps embracing the upper and lower springs and a pair of rollers carried by each of the clamps and receiving there-between the lowermost spring and contacting the surfaces of the springs, said clamps being substantially inverted U-shaped and the first named clamps at their closed ends being fixed to the end of the longest leaf of said leaves and the second named clamps at their closed end being fixed to a second one of said upper springs.

In testimony whereof we affix our signatures.

ALPHIE ROULEAU.
PAUL NADEAU.
